UNITED STATES PATENT OFFICE

153,226

DESIGN FOR AN ELECTRIC VAPORIZER

Nathaniel B. Milton, Los Angeles, Calif.

Application March 25, 1947, Serial No. 137,880

Term of patent 14 years

(Cl. D83—1)

To all whom it may concern:

Be it known that I, Nathaniel B. Milton, a citizen of the United States, residing in Los Angeles, county of Los Angeles, State of California, have invented a new, original, and ornamental Design for an Electric Vaporizer, of which the following is a specification, reference being had to the accompanying drawing, forming part thereof.

Fig. 1 is a perspective view of an electric vaporizer embodying my new design;

Fig. 2 is a top plan view; and

Fig. 3 is a front elevational view.

I claim:

The ornamental design for an electric vaporizer, as shown.

NATHANIEL B. MILTON.
